[57] CLAIM

The ornamental design for a adjustable desk lamp, as
shown and described.

DESCRIPTION

FIG. 1 is a top, rear, right side perspective view of an
adjustable desk lamp showing our new design, the lamp
in the collapsed position;

FIG. 2 is a right side elevational view thereof, the left
side being a mirror image;

FIG. 3 is a front elevational view thereof;

FIG. 4 is a rear elevational view thereof;

FIG. 5 is a top plan view thereof;

FIG. 6 is a bottom plan view thereof;

FIG. 7 is a top, rear, right side perspective view of the
lamp in the extended position;

FIG. 8 is a right side elevational view thereof, the left
side being a mirror image;

FIG. 9 is a front elevational view thereof;

FIG. 10 is a rear elevational view thereof;

FIG. 11 is a top plan view thereof; and

FIG. 12 is a bottom plan view thereof.
